UNITED STATES PATENT OFFICE.

GEORGE W. DERMAN AND JOSEPH A. MONIGHAN, OF SACRAMENTO, CALIFORNIA.

SAFETY-LOCK FAUCET.

Application filed October 1, 1923. Serial No. 665,886.

To all whom it may concern:

Be it known that we, GEORGE W. DERMAN and JOSEPH A. MONIGHAN, residing at Sacramento, county of Sacramento, State of California, have invented certain new and useful Improvements in Safety-Lock Faucets; and we do declare the following to be a full, clear, and exact description of the same, reference being had to the accompanying drawings, and to the characters of reference marked thereon, which form a part of this application.

This invention relates to improvements in faucets of the well-known "molasses gate" type, which are extensively used in connection with the dispensing and sale of lubricating oils in service stations and the like.

The oil containers are commonly set close to the floor or ground, so that the faucets, being at the bottom of the containers, are quite low down.

With use, the faucets of course become covered with oil, so that they tend to open very easily, and as they are now constructed, there is nothing to prevent accidental opening thereof by an inadvertent kick of the foot, or the like, which opening, if not noticed, may cause a considerable loss of oil, and at best is a constant source of annoyance to the operators.

The principal object of our invention is to eliminate the above named trouble by providing a faucet of this type with a safety catch or lock so arranged that its release is only had with a movement in a direction opposite to the direction of opening movement of the faucet.

In other words, to open the faucet, pressure in the necessary direction to do so must be combined with a simultaneous pressure in the opposite direction on the catch.

At the same time, the catch release trigger or handle is so arranged relative to the faucet handle that the faucet may be opened in the usual manner and with no more effort than is at present necessary in doing so.

A further object of the invention is to produce a simple and inexpensive device and yet one which will be exceedingly effective for the purposes for which it is designed.

These objects we accomplish by means of

such structure and relative arrangement of parts as will fully appear by a perusal of the following specification and claims.

In the drawings similar characters of reference indicate corresponding parts in the several views.

Fig. 1 is a side elevation of a faucet of the molasses-gate type, showing our improved safety lock mounted thereon.

Fig. 2 is a sectional elevation of the same.

Referring now more particularly to the characters of reference on the drawings, the numeral 1 denotes the body of the faucet, of standard design, threaded on one end as 2 for connection to a source of supply, and having a convexly curved face 3 on its other end, the bore 4 of the body terminating adjacent the lower end of this face. Slidable over this face, of smaller dimensions than the same, but larger than the mouth of the bore and adapted to cover or uncover the same, is a gate 5 pressed against said face by a spring 6 mounted in a cup 7 formed in a casing or shell 8 which normally covers the entire area of the face in spaced relation thereto and is mounted on the body by means of arms 9 extending to pivotal pins 10 fixed on the body, these pins being axially located with respect to the curvature of the face 3. A handle 11 is formed with the shell and projects outwardly thereof in central longitudinal alignment with the body.

For ease and economy of manufacture, the handle member is made in two symmetrical and equal sized parts, each hollowed out, and secured together by screws or bolts 12.

The foregoing construction and arrangement of parts are standard, and of themselves form no part of our invention, which comprises a pawl 13 pivoted on the upper one of the bolts 12 and located in the hollow area between the two parts of the gate-casing 8, as above described. The free end of this pawl is adapted to seat in a transverse notch 14 provided in the body-face 3 just above the gate 5 when the latter is in its closed position. Formed with said pawl is a handle member 15 projecting up through a recess 16 in the handle 11, and then overhanging said handle 11 substantially parallel thereto, and normally spaced therefrom. The pawl is normally held

seated in its notch by a spring 17 mounted in the structure 8.

The pawl and handle unit is substantially in the form of a bell crank, and so arranged that to withdraw the pawl from its notches the handle member 15 thereof must be depressed or moved toward the faucet-opening handle 11.

Since to open the faucet the handle 11 must be raised and to enable it to be so raised the pawl handle 15 must move down, it will be evident that a movement of either handle alone will not suffice to open the faucet, but both handles must be moved in their proper directions simultaneously.

It will thus be seen that it is impossible to accidentally open the faucet by upwardly directed pressure on the handle 11 alone, or by downwardly directed pressure on the pawl handle alone.

At the same time, it is no harder to open the faucet with our lock structure than without, since the handle 11 is usually grasped by the hand with the thumb on top, and it requires of course no more effort to place the thumb on top of the handle 15. Then with a downward pressure of the thumb, and an upward pressure of the hand as a whole—a very natural movement or operation—the pawl will be released and the gate 5 permitted to move from over the mouth of the faucet-opening.

A downward limitation of movement of the gate is had by means of a lip 8^a on the member 8 which overhangs the upper end of the body 1 and abuts thereagainst when the faucet is closed. Opening or upward movement of the member 8 and gate 5 is limited by a lip 3^a projecting outwardly from the upper end of the face 3, and against which the pawl 13 abuts when the gate 5 is clear of the faucet opening.

From the foregoing description it will be readily seen that we have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described our invention what

we claim as new and useful and desire to secure by Letters Patent is:

55

1. In combination with a faucet having a body provided with an outlet in one face thereof, a gate slidable over said face to cover or uncover the outlet, and a hollow handle member in which the gate is mounted normally enveloping the outlet-face of the body, a catch member mounted in the handle above the gate and engaging the body-face when the gate is closed, and a releasing member for said catch member extending through and above the handle and compressible theretoward to release the catch, the gate being opened by a movement of the handle in an upward direction.

2. In combination with a faucet having a body provided with an outlet in one face thereof, a gate slidable over said face to cover or uncover the outlet, and a catch means mounted in connection with the sliding gate and normally preventing opening movement thereof, said catch being releasable only by pressure exerted in a direction directly opposite to that necessary to open the gate.

3. In combination with a faucet having a body provided with an outlet in one face thereof, a gate slidable over said face to cover or uncover the outlet; a catch member engageable with the body when the gate is closed and mounted in connection with the gate, and releasing means for said catch disposed to be moved in a direction directly opposite to that necessary for the opening of the gate.

4. In combination with a faucet having a body provided with an outlet in one face thereof, a gate slidable over said face to cover or uncover the outlet and a handle for moving said gate; a catch member engageable with the body when the gate is closed and mounted in connection with the gate, and a releasing handle for said catch positioned adjacent the gate handle and in the path of opening movement thereof, said catch handle being movable to release the catch only in a direction directly opposite to that of the opening movement of the faucet handle.

Is testimony whereof we affix signatures.

GEORGE W. DERMAN.

JOSEPH A. MONIGHAN.
